US00D897463S

(12) **United States Design Patent** (10) **Patent No.:** **US D897,463 S**
Parsons et al. (45) **Date of Patent:** **** Sep. 29, 2020**

(54) **GOLF CLUB HEAD**(71) Applicant: **PARSONS XTREME GOLF, LLC**,
Scottsdale, AZ (US)(72) Inventors: **Robert R. Parsons**, Scottsdale, AZ
(US); **Bradley D. Schweigert**, Anthem,
AZ (US); **Michael R. Nicolette**,
Scottsdale, AZ (US)(73) Assignee: **PARSONS XTREME GOLF, LLC**,
Scottsdale, AZ (US)(***) Term: **15 Years**(21) Appl. No.: **29/689,664**(22) Filed: **May 1, 2019****Related U.S. Application Data**

(60) Division of application No. 29/661,121, filed on Aug. 24, 2018, now Pat. No. Des. 850,551, which is a continuation-in-part of application No. 29/646,576, filed on May 4, 2018, now abandoned, which is a continuation-in-part of application No. 29/646,582, filed on May 4, 2018, now abandoned, which is a continuation-in-part of application No. 29/645,048, filed on Apr. 23, 2018, now abandoned, which is a continuation-in-part of application No. 29/634,923, filed on Jan. 25, 2018, now abandoned, which is a continuation-in-part of application No. 29/628,987, filed on Dec. 9, 2017, now Pat. No. Des. 839,372, which is a continuation-in-part of application No. 29/628,986, filed on Dec. 9, 2017, now Pat. No. Des. 827,745, which is a continuation-in-part of application No. 29/616,688, filed on Sep. 7, 2017, now abandoned, which is a continuation-in-part of application No. 29/610,183, filed on Jul. 10, 2017, now abandoned.
